UNITED STATES PATENT OFFICE.

ALVIN TAYLOR CHURCH, OF FARMINGTON, IOWA.

SASH-HOLDER.

SPECIFICATION forming part of Letters Patent No. 357,578, dated February 15, 1887.

Application filed June 17, 1886. Serial No. 205,451. (No model.)

To all whom it may concern:

Be it known that I, ALVIN TAYLOR CHURCH, a citizen of the United States, residing at Farmington, in the county of Van Buren and State of Iowa, have invented certain new and useful Improvements in Sash Holders and Locks; and I do hereby declare the following to be a full, clear, and exact description of the invention, such as will enable others skilled in the art to which it appertains to make and use the same, reference being had to the accompanying drawings, which form part of this specification.

My invention relates to that class of side attachments for windows for the purpose of holding the sash, and has for its object a device so constructed that by means of a lever-arm a beveled shaft-head can be turned against a beveled lug on an angle-piece in a socket of a window-sash stile to hold a roller therein against the casing of the window, thereby locking the sash at any desired point; and it consists in the construction hereinafter described, and more particularly pointed out in the claims.

Referring to the drawings, Figure 1 represents my invention applied to a window-sash in a casing ready for use, the sash being broken away to show the device. Fig. 2 is a plan view of the angle-piece holding the roller in the socket. Fig. 3 is a plan view of the socket with the angle-piece removed, showing the beveled head of the shaft. Fig. 4 is a perspective view of the angle-piece, representing the beveled lug on its under side. Fig. 5 is a view of the lever-arm and shaft, with beveled head having a coiled spring and washer thereon.

Like letters of reference refer to corresponding parts in each figure of the drawings. A represents a window-jamb or casing, and B a window-sash to slide up and down therein. In the outer edges of the sash-stile C a socket, e, is made by cutting an inwardly-beveled opening from the outer side of the stile in shape adapted to hold my fastening device.

At or near the upper and outer edge of the socket there is hinged or pivoted an angle-piece, D, that rests within the socket, so that its angle-arm d on its lower end can pass into the socket a sufficient distance to be within the outer edge of the sash-stile C.

On the inner side of the main arm d' of the angle-piece, and at or near the angle-arm d, there is a beveled lug, a, extending a part of the way up the main arm as it lies in the 55 socket, for the beveled head of a lever-shaft to work against to prevent its frictional contact with the main arm.

In the bottom of the socket a recess, E, is made, from which a hole, e, is extended through 50 the sash-stile. Within this hole and recess a shaft, F, having a hinged lever-arm, G, is inserted through the socket from the outer side of the sash-stile. On the outer end of the shaft there is a head, f, having a beveled end, which 65 is made to bear against the beveled lug a on the inner side of the main arm d' of the angle-piece, and on the inner side of the head there is placed a washer, b, adapted to fit in the bottom of the socket e, for the head of the shaft to 70 rest upon when it is turned. Between the washer and lever-arm a coiled spring, H, is placed on the shaft, which fits into the recess E in the bottom of the socket and bears against the washer to hold the beveled head f of the 75 shaft against the beveled lug on the angle-piece.

The angle-piece D is constructed to hold a roller, I, at its lower end on its angle-arm d, which is gradually pressed against the casing by the action of a coiled spring, H, to hold the 80 sash in position.

In operation, as the window-sash is raised, the roller turns on the arm d of the angle-piece by its gentle frictional contact with the casing A, and when at its desired height, and 85 the movement of the sash is reversed, the roller at once rides up on the inclined main arm d' of the angle-piece, and so binds against the casing and the angle-piece as to prevent a further descent of the sash. When it is desired 90 to lower the sash, it is slightly raised and the lever-arm G is grasped with one hand and the shaft slightly withdrawn to overcome the action of the spring H, and held in that position when the roller falls down upon the angle-arm 95 d, and the sash slides down in the casing without resistance.

The device forms a cam-lever lock for window-sash, and is adapted to fasten them at any desired point.

The beveled head f of the shaft being in the socket, with its thin edge extending downward,

with the lug *a* on the lower portion of the angle-piece resting on and being of the same inclination as the head in this position, the lever-arm *G* is given a partial turn, bringing one edge of the middle or thickened part of the beveled head at the lowest point of the head in place of the thin edge, thereby crowding the angle-piece outward and pressing the roller *I* against the casing *A*, locking the sash in position. When there is sufficient space between the window stile and casing, the lever-arm is turned upward until it strikes the glass, thereby bringing the thickest part of the beveled head at the lowest point of the head, crowding the angle-piece outward still farther, with the same result as above set forth. By this construction a secure lock is formed, as well as a holder for a sash, which can be loosened from the outside only by breaking the glass.

Having thus fully described my invention, what I claim as new, and desire to secure by Letters Patent of the United States, is—

1. A combined sash holder and lock, consisting of an angle-piece hinged in a socket in a sash-stile and having a free roller thereon, with a cam-lever at or near the end of the inner side of the angle-piece opposite the hinged

end, adapted to press the roller against the window-casing and lock the sash in position, substantially as and for the purpose set forth. 30

2. The combination, with a sash-stile having a socket with an angle-piece hinged therein, carrying a free roller and provided with a beveled lug on its inner side, of a shaft secured in the sash-stile on the inside of the angle-piece, having a head with a beveled end adapted to work over the lug to lock the sash in position, as set forth. 35

3. A sash-stile having a socket with an inclined angle-piece hinged therein carrying a free roller, said angle-piece having a beveled lug on the inner side of its main arm, and a shaft in the socket passing through the sash-stile and provided with a hinged lever-arm on its inner end and a beveled head on its outer end, held against the lug on the angle-piece by a spring and adapted to work over the lug to hold and lock the sash, substantially as set forth. 40

In testimony whereof I affix my signature in presence of two witnesses.

ALVIN TAYLOR CHURCH.
